UNITED STATES PATENT OFFICE.

CHARLES W. HAMILTON, OF BAKERSFIELD, CALIFORNIA.

FLUE-CLEANER FOR STEAM-BOILERS.

1,076,362.

Specification of Letters Patent.

Patented Oct. 21, 1913.

Application filed July 19, 1912. Serial No. 710,417.

To all whom it may concern:

Be it known that I, CHARLES W. HAMILTON, a citizen of the United States, residing at Bakersfield, in the county of Kern and 5 State of California, have invented new and useful Improvements in Flue-Cleaners for Steam-Boilers, of which the following is a specification.

This invention relates to flue cleaners for 10 steam boilers and has for an object to provide apparatus of this character wherein means are provided for connecting a main blast pipe with a fluid source such as the boiler itself so that sufficient steam pressure 15 will be carried to the pipe and then conducted therefrom to the boiler flues with the resultant effective cleaning of such flues.

Another object of the invention is to provide a flue cleaning apparatus which will 20 embody parts that are capable of being folded together and conveniently removed from the boiler when not in use.

In the drawing forming a portion of this application and in which like letters of reference indicate similar parts in the several views:—Figure 1 is a longitudinal section through a boiler and through the boiler flues, illustrating the attachment of the cleaning apparatus thereto. Fig. 2 is a 25 front view of the boiler showing the application of the flue cleaner thereto and illustrating in dotted lines different positions of the blast pipe. Fig. 3 is a longitudinal section through the apparatus showing the nozzle in an opened position. Fig. 4 is a longitudinal section taken on line 4—4 of Fig. 3. Fig. 5 is a perspective view of the nozzle. Fig. 6 is a perspective view of the valve. Fig. 7 is a perspective view of a portion of 30 the valve rod showing the manner of connecting the controlling lever therewith.

The apparatus comprises a pipe or main conduit 1 which is closed at one end as at 2 and provided adjacent to the said closed 45 end with an opening 3 whereby communication is established between the pivoted nozzle 4 and the pipe 1. The nozzle is pivoted at 5 upon the pipe 1, and as illustrated the nozzle is provided with an extension or 50 bracket like portion 6 which is movable across a similar extension 7 of the pipe 1.

A combined nozzle adjusting and valve controlling rod 8 is slidable longitudinally in the pipe 1 and through the closed end 2 thereof, being provided beyond said closed end with a right angularly extending por-

tion 9 which extends through an elongated slot 10 in the bracket 7. The portion 9 is pivoted at 11 to one end of an arcuate link 12, while the opposite end of the latter is 60 pivotally connected at 13 to the extension 6 of the nozzle 4, whereby the nozzle can be adjusted angularly with relation to the pipe 1 when the rod 8 is moved longitudinally in the pipe 1. The nozzle 4 is provided with 65 a curved discharge end 14 which is adapted to be closed by a seat 15 which extends from one side of the pipe 1 as shown in Fig. 3. The rod 8 is slidable through a T-coupling 16 at the actuating end of the pipe 1. This 70 coupling is connected with a branch pipe 17 by a lateral pipe section 18. The pipe 17 carries a coupling member 19 which may be connected in any suitable well known manner with a hose which may lead from 75 any suitable source of steam supply. A plug 20 closes the branch 22 of the T-coupling 16 and as shown the said plug is connected by a radial pipe section 22 with an actuating handle 23, the latter having a longitudinal slot 24 therein for a purpose to be hereinafter explained. The valve rod is provided with a collar 25 from which extends a pin 26. A controlling lever 27 is pivoted at 28 to the pipe 17 while the opposite end of the lever is extended through the slot 24 and into the handle 23 whereby to be guided in its movement thereby. The intermediate portion of the controlling lever 27 has an elongated slot 29 therein 80 through which the pin 26 of the collar 25 extends whereby to compensate for longitudinal 85 adjustments of the rod 8.

The rod 8 is connected with a cylindrical valve 30 which is mounted for sliding movements in the pipe 1, being adjustable across port openings 31 in the pipe as clearly shown in Fig. 3 whereby when the lever 27 is adjusted to close the nozzle 4 against the seat 15 the portways 31 will be opened by 100 said valve, while on another adjustment of said lever to open the nozzle to the position shown in Fig. 4 or to any other position past the seat 15, the valve will be influenced so as to close the said port openings. 105

Now that the details of construction of the cleaning apparatus are clearly described it is seen that when it is desired to clean the flues of a boiler the pipe 1 may be extended through the wall A of the boiler B 110 and through the lowermost flue C whereby the nozzle end of the pipe 1 will extend con-

siderably beyond the front end of the boiler. The coupling 19 is then connected in any suitable source of steam supply whereby the steam may be introduced to the pipe 1 and 5 then finally discharged from the nozzle. The lever 27 may be manipulated to effect any required angular adjustment of the nozzle that might be desired to bring adjacent flues directly in the path of the discharge end of the nozzle where they will 10 be directly subjected to steam blasts that will emanate from the nozzle. It is of course understood that the handle 23 is manipulated manually so as to cause the 15 pipe 1 to be properly oscillated in the flue.

The apertures 31 are adapted to be disposed in line with the smoke box and smoke stack respectively of the boiler whereby when the valve 30 is in the position shown 20 in Fig. 3 steam emanating from said passages will be permitted to relieve said smoke stack and the smoke box of the accumulated soot.

I claim:—

- 25 1. A flue cleaner for boilers comprising a fluid feeding conduit, a nozzle adjustable angularly thereon and arranged in open communication therewith, a controlling lever at the intake end of the conduit and a rod 30 connecting the lever with the nozzle, the said conduit having an opening therein at one side, and a valve carried by the rod and movable over the said opening on longitudinal adjustments of the rod.

2. A flue cleaner comprising a conduit 35 having one of its ends closed and its other end provided with a fluid inlet, a handle on said fluid inlet, said conduit having a lateral passage therein, an adjustable nozzle carried by the conduit and communicating therewith 40 and located adjacent to the closed end thereof, and means for effecting adjustment of the nozzle and including a sliding valve in the conduit movable with relation to said lateral passage on different adjustments of 45 the nozzle.

3. A flue cleaner comprising a conduit having one of its ends closed and its other end provided with a fluid inlet, a handle on said fluid inlet, said conduit having a 50 lateral passage therein, an adjustable nozzle carried by the conduit and communicating therewith and located adjacent to the closed end thereof, means for effecting adjustment of the nozzle and including a sliding valve 55 in the conduit movable with relation to said lateral passage on different adjustments of the nozzle, and a fixed seat exteriorly mounted upon the conduit and operable to engage against the discharge end of the nozzle to 60 close the same when the nozzle is projected to one position.

In testimony whereof I affix my signature in presence of two witnesses.

CHARLES W. HAMILTON.
